UNITED STATES PATENT OFFICE.

AUGUST H. HERZOG, OF MISHAWAKA, INDIANA.

FOOT-RAIL FOR COUNTERS.

SPECIFICATION forming part of Letters Patent No. 470,348, dated March 8, 1892.

Application filed November 7, 1891. Serial No. 411,167. (No model.)

To all whom it may concern:

Be it known that I, AUGUST H. HERZOG, of Mishawaka, in the county of St. Joseph, and State of Indiana, have invented new and 5 useful Improvements in Foot-Rails for Counters; and I do hereby declare that the following is a full and accurate description of the same, reference being had to the accompanying drawings, wherein—

10 Figure 1 is a perspective view of my invention in operative position. Figs. 2 and 3 are side elevations showing the same in two positions. Figs. 4, 5 and 6 are modifications.

It is customary to provide lunch-counters 15 and the like with rails for the convenience of persons standing in front to support one or both the feet. This rail is eight or ten inches above the floor and about the same in front of the counter. This rail cannot be efficiently 20 supported by brackets attached solely to the front of the counter because of the difficulty of so securely fastening the brackets to the front of the counter that the pressure of the feet will not cause said fastenings to become 25 loose. For that reason said rail is commonly supported from the floor, and when so supported the posts are in the way when sweeping or washing the floor. I am aware that to 30 obviate this objection the rail has been provided with a foot to rest on the floor and an arm hinged to the front of the counter, or a short bracket projecting therefrom, so that when the floor is to be cleansed the rail and its several supporting-feet may be raised up, 35 turning upward and backward on said joints and leaving the floor clear to the base of the counter. This device is objectionable because it makes it necessary to move the rail as an 40 entirety and because it cannot be operated in that way around corners or in other than straight lines and moderate lengths.

My improvement removes all objections 45 above noted and secures equally easy access to the floor below the rail, unobstructed by the supporting-feet, while the rail itself may be continuous, of any length, and permanent in its location.

That the structure of my invention may be fully understood, I will particularly describe it.

A is the counter, and B is the ordinary foot- 50 rail, above described.

C C are ordinary brackets attached to the front of the counter A and supporting the foot-rail at their outer extremities.

D D are the supporting-feet, which rest 55 upon the floor and directly sustain said foot-rail under any load which may be imposed upon it.

The feet D are jointed to the rail B or to the brackets C in some suitable way, so that 60 when in position resting upon the floor they will afford the required support to the rail, and when the floor is to be cleansed they may be turned up out of the way. Ordinarily I have hinged them directly to the rail by passing 65 the rail through the joint-eye of the foot, as shown in Figs. 1 to 5; but it is evident a similar result may be secured by hinging the foot to the bracket C independent of the rail B, as shown in Fig. 6 by way of illustration. 70 It will be apparent that this pivot can be arranged in a variety of ways without changing the character of the invention.

Having described my invention, I claim—

1. A foot-rail for counters, provided with 75 permanent brackets, whereby said rail is supported independent of the floor, and hinged feet capable of being removed from contact with the floor, for the purpose set forth.

2. A foot-rail B and brackets C, connected 80 with and supporting said rail independent of the floor, combined with hinged or movable feet D to rest on the floor and support said rail directly and be removed from the floor when it is desirable to cleanse the same. 85

3. A foot-rail B and supporting-brackets C, attached to the counter and supporting said rail independent of the floor, and the feet D, hinged to the rail B, as set forth.

4. A foot-rail B, permanently mounted upon 90 brackets C independent of the floor, and the individually-movable feet D, substantially as set forth.

AUGUST H. HERZOG.

Witnesses:

HENRY GILBERT,
JOHN A. HERZOG.
